PROCESS AND APPARATUS FOR
DEWAXING OILSDavid R. Merrill, Long Beach, Calif., assignor to
Union Oil Company of California, Los Angeles,
Calif., a corporation of California

Application May 22, 1934, Serial No. 726,969

23 Claims. (Cl. 62—170)

The present invention relates to a process and apparatus for separating wax from mineral oils such as from petroleum, its residues or overhead fractions and from wax-containing lubricating oil stocks for the production of lubricating oils of low pour point. The invention more particularly relates to a process and apparatus for chilling wax-containing oils in order to obtain a controlled precipitation of the wax from the wax-containing stocks.

In lubricating stocks, especially those of considerable viscosity range or boiling range, there will normally be present waxes varying widely in characteristics comprising at the one extreme, hard waxes of relatively high melting point, such as, for example, 150° F. and at the other extreme, soft waxes of relatively low melting point, such as, for example, 110° F. Although ordinarily only a small proportion of the total wax content in the lubricating oil stock will consist of hard waxes, their presence in the waxy stock is very important since they have such a low solubility in the solution of waxy oil and diluent and are usually the first type of wax to separate on gradual cooling. Also because of the low initial concentration in the solution such hard waxes are precipitated in a very finely divided form on excessively rapid chilling and also because of their low solubility show little tendency towards resolution of these fine particles and crystal growth. It is, therefore, evident that the most critical temperature range is that in which the initial separation of wax occurs because if an excessive number of nuclei are formed at this time there is little possibility of correcting this situation by subsequent digesting operations. It is an object of my invention to control the formation of nuclei during the initial stages of wax separation so as to prevent formation of an excessive number of such nuclei and to permit further crystal growth on nuclei formed in the early stages of chilling.

In general, crystallization of wax is accomplished by inducing a supersaturated condition in the solution of waxy oil and solvent employed to dilute the oil. This is accomplished either by increasing the concentration of the solute by vaporization or separation of solvent, or by reducing the solubility by cooling, or both. Some investigators have shown there is a narrow range of concentration and a corresponding range of temperature of supersaturation within which free formation of new crystal nuclei will not occur. In this range of supersaturation, crystallization will occur on nuclei already present but

formation of new nuclei will occur to only a very limited extent, if at all. This range of supersaturation is commonly referred to as the metastable range. For purposes of definition, the metastable range of supersaturation is that range of supersaturation within which crystallization occurs on the surfaces of crystals already present and spontaneous formation of new crystal nuclei in large amount does not occur.

As soon as the metastable range of supersaturation is exceeded, however, a so-called labile range of supersaturation is reached in which rapid formation of new crystal nuclei will occur. Thus, the labile range of supersaturation denotes a degree of supersaturation in which spontaneous formation of new crystal nuclei occurs to a very large extent. With a slow rate of chilling, the rate of crystallization upon the wax nuclei already present is sufficiently rapid to relieve the supersaturation and permit crystallization to occur within the metastable range so that uncontrolled formation of new nuclei does not occur. With an excessively rapid rate of chilling, however, the degree of supersaturation exceeds the metastable range and this results in the formation of large numbers of new nuclei and consequent reduction in the average particle size due to the production of a large amount of fine particles which are of a gelatinous or slimy character. A wax slurry of this character is difficult to separate from the oil solvent solution by either settling or filtering. The permissible rate of chilling will, of course, depend not only on the extent of the metastable range but also upon the rate at which supersaturation is relieved by crystallization upon particles of wax already present. It is another object of my invention to control conditions and rate of chilling in dewaxing operations within the metastable range of supersaturation and to relieve supersaturation by crystallization of wax on wax particles already present in the solution.

In one of the known methods for separating wax from oils, the oil is mixed with a hydrocarbon solvent, more particularly a liquefied normally gaseous hydrocarbon solvent, such as liquid propane. The admixture is effected under a pressure sufficient to maintain the solvent in the liquid phase. Thereafter, a portion of the solvent is vaporized under reduced pressure in order to effect chilling and precipitation of wax from solution. In the case of propane, by reducing the pressure down to atmospheric, a temperature of approximately —40° F. may be obtained in the remaining oil and solvent solution. The wax

which precipitated during the chilling operation is then removed by settling, filtering or centrifuging. The remaining propane may then be removed from the dewaxed oil by distillation.

5 In dewaxing lubricating oils by the use of liquefied normally gaseous hydrocarbons such as propane, it has been found that in batch operation the rate of chilling must be very carefully controlled because when the chilling is accomplished at an excessive rate, a wax slurry is formed which is very difficult to separate from the oil and remaining solvent by such means as settling or filtering. It is usually found undesirable to exceed a chilling rate of about 3° F. per minute in the temperature range from about the temperature at which wax begins to precipitate from solution or the cloud point of the oil solution down to the final dewaxing temperature. However, more rapid chilling may more often be 10 carried out between the temperature ranges of 0° F. and the usual final temperature of about -40° F. Preferably, however, the rate of chilling should not be more than 3° F. per minute from the cloud point of the solution down to the 15 final temperature of -40° F. While such control of chilling rate in batch operations is relatively simple and can be accomplished readily in chilling by internal refrigeration merely by drawing off the propane vapor at a suitably controlled rate so that the pressure of the vapor above the liquid falls at a rate corresponding with the desired rate of reduction of temperature, controlled chilling under the conditions of continuous flow is more difficult to accomplish because it has usually been necessary in the past to employ a definite number of stages with definite pressure differences between each stage. These pressure differences correspond with definite differences in 20 temperature and the tendency is for the temperature of the stream to drop immediately, due to flash vaporization, as soon as the pressure is reduced on passage through the control valve in the line connecting the stages. It is thus another object of my invention to accomplish controlled chilling under conditions of continuous flow and to obtain results similar to controlled vaporization of solvent in batch chilling operations.

Various other objects and features of my invention will become apparent to those skilled in the art from the following description of my invention taken from the drawings.

I have discovered that by utilizing the hydrostatic pressure of the solvent oil solution containing wax for controlling the pressure at various points in a continuous chilling system in which a liquefied normally gaseous hydrocarbon such as propane is employed as an internal refrigerant-diluent I may accomplish results similar to controlled vaporization of solvent under reduced pressure in batch chilling operations. The method for accomplishing utilization of hydrostatic pressure for controlling continuous chilling in dewaxing operations will be better understood from the following description taken from the drawings in which:

Fig. 1 represents a general flow diagram of arrangement of apparatus adapted to carry out my process.

70 Figs. 2, 3, and 4 represent modifications of arrangements of chillers adapted to control vaporization of solvent during the chilling operations by hydrostatic pressure.

Referring to Fig. 1, a wax-containing oil such as an S. A. E. 40 waxy distillate produced from

Santa Fe Springs crude oil is taken from tank 1 and is passed via line 2 by pump 3 which forces the oil through line 4 and heater 5 and then via line 6 into line 7 where it meets a stream of liquefied normally gaseous hydrocarbon solvent such as liquid propane which has been withdrawn from tank 8 via lines 9 and 10 and pump 11. Approximately 6 volumes of propane are mixed with one volume of waxy oil. The waxy oil and liquid propane brought together by means of separate pumps are passed through mixer 12 and thence through heat interchanger 14, line 15 and heater 16 where the temperature of the solution is raised to that at which the wax is completely in solution as, for example, 130° F. The mixture then passes via line 17 through heat interchanger 18, line 19 and cooler 20 where the solution is cooled down to a temperature which is definitely above the temperature of initial separation of wax although preferably the temperature may be reduced to approximately a few degrees above the cloud point of the oil-diluent mixture. Pressure is controlled by means of relief valve 22 on line 21. This valve is employed for the purpose of maintaining sufficient pressure in the heater 16 to prevent flashing in the heater.

The stream of oil and propane is then led into the bottom of the first of the series of chillers 23, 23a, 23b, and 23c. Each chiller is provided with a plurality of baffles 27 which extend across the column so as to provide a plurality of chilling stages or sections or chambers 28 within which liquid and vaporized propane may collect. The sections 28 are preferably staggered so that the propane vaporized from the solution passing through the space 29 may collect in the superimposed section. Each section of each chiller is provided with a float control 30 so as to maintain a definite level of liquid in the section. The vapors trapped in each section are withdrawn via line 31 controlled by valve 32 and pass into headers 33. The pressure at the bottom of each chiller is equal to the sum of the hydrostatic head of liquid in the chiller and the pressure of the propane vapor at the top of the chiller which pressure is maintained at a definite value by control of the operation of compressors 35, 35a, 35b, and 35c. The pressure at the bottom of each chiller will preferably be maintained exactly equal to the vapor pressure of the entering stream at the entering temperature so that no appreciable flashing occurs upon passage of the stream through the back pressure control valves 22 and 31.

On continued flow of the solution of waxy oil and propane in the first chiller 23, the solution rises in the tower and the pressure upon it becomes gradually less due to the reduction of the hydrostatic head. As soon as the external pressure becomes less than the vapor pressure, vaporization takes place at any free surface provided and to some extent in the body of the liquid. The vaporized propane is trapped off and collected in the chambers 28 from which it is withdrawn via lines 31 and level control valves 32 into header 33. The collection of vapor and trapping off under float control maintains a definite level of liquid. Due to vaporization and to mixing by eddy currents, the temperature of the mixture is gradually reduced as it rises in the tower and when it reaches the top of the tower the temperature is substantially that corresponding with the pressure maintained by the control of compressor 35. It is thus apparent that there is a definite and gradual drop in temperature as the mixture passes up the tower. By proper design so as to

maintain a sufficient volume of liquid in the tower, the rate of cooling of the stream can be readily controlled. Due to the relatively low specific gravity of the propane solution, the height of the tower required will be about 4 ft. for each pound drop in pressure. The number of towers and of stages shown in each tower is merely by way of illustration and in practice considerably more stages would be desirable, as except for eddy currents in the passage past the vapor collecting chambers some fall in temperature will tend to be concentrated in the zone at the entrance of the stream into the mixture under the vapor collection chambers. The cooling at this point, however, if a sufficient number of chambers is provided will be largely by mixing rather than by flashing. Such cooling will not result in the metastable range of supersaturation being exceeded unless the drop in temperature is large in proportion to the extent of recirculation.

Upon reaching the top of the first chiller the solution flows down through line 36 and valve 37 which is actuated by a float control 38 in the first chamber. It will be noted that this valve is located at a low level so that the pressure on the down stream side of the valve will not be less than the vapor pressure of the solution as would be the case if it were located at the high level. In this way flashing upon passage through the valve is avoided. The pressure at the bottom of the second column 23a made up of the sum of pressure vapor at the top and the hydrostatic head is preferably maintained exactly the same as the pressure at the top of the first column 35 so that there will be no flashing of the entering stream and the chilling may continue at a uniform rate. The flow of liquid through the second column 23a and subsequent columns 23b and 23c and the removal of vaporized propane is accomplished in exactly the same manner as in the first column 23. The pressure at the top of columns 23a, 23b, and 23c is controlled by compressors 35a, 35b and 35c. It is apparent that the number of columns provided should be sufficient so that the chilled solution leaving the top of the last column will be at the desired dewaxing temperature as, for example, -40° F. If desired, after a temperature of about 0° F. is reached and most of the wax is precipitated, further chilling may be carried out at a more rapid rate or even by a flashing operation with only moderate deterioration in the filtration or settling characteristics of the wax slurry. The chilling in the range from 0° F. to the final temperature of -40° F. may also be accomplished by mixing with a recirculated stream of chilled mixture at -40° F. If the wax is of such character that deleterious quantities of fine particles would not be formed, a simple flashing operation may be carried out to chill the oil from about 0° F. down to -40° F. Where the oil being chilled does not contain sufficient propane to accomplish the desired chilling, further quantities may be introduced through lines 42 controlled by valves 43.

In order to avoid excessive height of equipment, the chiller is preferably made up of a number of stages or towers as shown but this is not essential. The pressure and temperature conditions at the bottom of the second tower, for example, are preferably maintained exactly the same as at the top of the first tower and this relation is maintained in the subsequent stages so that in effect the different stages represent continuously changing conditions in the stream. For example, when it is desired to chill the oil-

propane solution from 90° F. to -40° F. the oil-propane solution in line 21 at a temperature of 90° F. and under a pressure of 153 lb. gauge is introduced into the bottom of the first chiller 23 under the aforesaid conditions. In rising in the tower the solution is cooled by vaporization of propane at each of the stages due to the lessening of the hydrostatic head. If the chilling system is divided into four towers as shown in the drawings, the vapor pressure at the top of first 10 tower is maintained at about 111 lb. gauge by compressor 35 which corresponds to about 70° F. The oil and propane at the top of tower 23 is introduced into the bottom of the second tower 23a under the same pressure and temperature 15 conditions existing at the top of the preceding tower. In tower 23a, vaporization of propane cools the stream to approximately 42° F. when it reaches the top of the tower. A pressure of about 69 lb. gauge is maintained at the top by compressor 35a. The oil and propane under the same temperature and pressure conditions at the top of tower 23a is introduced into tower 23b in which it is cooled to 0° F. as it rises to the top of the tower. A pressure of about 27 lb. gauge is 25 maintained at the top of the tower by compressor 23b. The chilled oil and propane is next introduced into the bottom of the last chilling stage 23c at 0° F. in which it is chilled to -40° F. by vaporization of propane as it reaches the top of 30 tower 23c. A pressure of 0 lb. gauge is maintained at the top of the tower by compressor 23c.

Although in the drawings, a float control is shown on the vapor leaving the top of the column, it should be understood that this is only a 35 safety precaution as the level at this point will normally be controlled by the flow of liquid to the next stage. The float control actuating the valve on the vapor line will preferably be so adjusted as to close this valve only if an abnormally high 40 liquid level is reached.

The propane vapors separated from the various towers passing into headers 33 and to compressors 35, 35a, 35b, and 35c pass into header 38 and then through line 39 to cooler 40 where 45 the compressed vapors are liquefied and then pass via line 41 into propane storage tank 8. Although in the drawings the valves 32 are shown all connected to the same headers, in practice it is often more desirable to have several 50 headers operating at different pressures so as to reduce the power required for compression by avoiding unnecessary expansion and recompression.

The chilled oil and remaining propane solution containing precipitated wax preferably in 55 the ratio of approximately 3½ to 4 volumes of propane to one of the oil and wax is withdrawn from the top of the last chilling tower 23c at a temperature of -40° F. via line 45 by means of pump 46 which forces the mixture into the vapor 60 tight wax separator or settler 47. Make-up propane at -40° F. may be introduced into the chilled oil via line 44 controlled by valve 44' in order to provide for adequate settling or filtration of the precipitated wax. In order to prevent 65 ebullition or boiling in the wax separator during the wax settling operation, pressure is imposed upon the solution of oil. This is accomplished by maintaining pressure within the separator by pump 46. As the chilled mass in the wax separator 70 remains in a non-ebullient state, the wax settles out and is collected by vanes 48 on shaft 49 which is operated by belt 50 connected to a suitable source of power not shown. The wax-free oil dissolved in propane is withdrawn from the 75

separator 47 via line 51 and is passed into collecting tank 52.

The precipitated wax slurry containing propane settling at the bottom of the wax separator 47 is removed through line 52 and pumped by pump 54 into line 55 where it meets a stream of chilled recovered oil and propane from surge tank 56 via line 57 and pump 58. The two streams then pass through line 55 and mixer 59 into settler 60 which is constructed in a manner similar to settler 47 and in which the wax from settler 47 is washed with the dilute oil propane solution from surge tank 56. Oil and propane separated from the wax slurry is withdrawn via line 61 and passed into collecting tank 52. The once washed wax slurry is withdrawn from the bottom of settler 60 via line 62 and pump 63 which forces the wax slurry through line 64 wherein it meets a stream of chilled propane at -40° F. coming from chilled propane storage tank 65 via line 66, pump 67, line 68 and valve 69. The mixture then flows through mixing coil 70 into another settler 71 constructed similarly to settlers 47 and 60. In settler 71 the wax from settler 60 is washed with the fresh chilled propane and any oil separated is withdrawn together with the chilled propane via line 72 and passed into surge tank 56. As stated previously, this solution containing a small amount of recovered oil is employed to wash the wax slurry from the first settler 47. The countercurrent washing steps may be carried on in as many stages as desired. The chilled propane in tank 65 is produced by withdrawing a portion of the propane under pressure from tank 8 via lines 9 and 75, cooling it in heat interchangers 76 and 77 and passing it into tank 65. The propane in 65 is chilled to -40° F. by vaporizing a portion through line 78 and compressor 79 which forces the vaporized propane through lines 80, 81 and 39, cooler 40, line 41 into propane storage tank 8.

The substantially oil-free wax is withdrawn from the bottom of settler 71 via line 82 and pump 83 which forces the wax through line 84, heat interchanger 85, line 86 into high pressure exhauster 87 where vaporized propane under high pressure is withdrawn via line 88 into line 89. Wax in exhauster 87 is continuously recirculated from the bottom into the top of the exhauster via line 90, pump 91, line 92, heater 93 and line 94. The wax, or a portion thereof, is then passed through valve 95, line 96, heater 97, line 98 into the low pressure exhauster 99. Vaporized propane under low pressure is withdrawn via line 100, compressed in compressor 101 and passed into line 89. Wax in low pressure exhauster 99 is recirculated via line 102, pump 103, valve 104, line 96, heater 97 and line 98. Substantially propane-free wax is withdrawn through valve 105 and passed through cooler 106, line 107 into wax storage tank 108 where it is maintained, melted by steam circulated through coil 109.

The substantially wax-free oil and propane from collecting tank 52 is withdrawn via line 110 and pumped by pump 111 through line 112, heat interchanger 114, line 115, valve 116 into high pressure exhauster 117 where vaporized propane under high pressure is withdrawn via line 118. The oil in high pressure exhauster 117 is continuously recirculated through line 119, pump 120, line 121, heater 122 and line 123. The oil containing the remaining propane is then passed through valve 124, line 125, heater 126, line 127 into low pressure exhauster 128. Propane and oil from the low pressure exhauster is continuous-

ly recirculated through line 129, pump 130, valve 131, line 125, heater 126, line 127 into exhauster 128. Vaporized propane under low pressure is withdrawn from low pressure exhauster via line 132 and passed into line 100, compressed in 101 and passed into line 89. Substantially propane-free oil is withdrawn from the low pressure exhauster via line 129, pump 130, valve 133, line 134 and passed into storage tank 135 which is cooled by cooling coil 136. The propane vaporized from the low and high pressure exhausters and collecting in lines 89 and 118 is passed into lines 137, 81 and 39, cooler 40, line 41 into propane storage tank 8.

In the foregoing disclosure I have described a method for utilizing hydrostatic pressure of the propane oil solution for controlling the pressure at various points in a continuous chilling system in which propane is employed as an internal refrigerant. In the system just described, float valves are employed for controlling the flow of vapor from each stage of vapor evolution. In the equipment shown in the drawings, a number of stages are placed one above the other in a column for convenience of construction but this, of course, is not essential and each stage may be constructed separately, if desired. In the following description of Figs. 2, 3, and 4 I have illustrated other methods of control while retaining the use of hydrostatic head as a means of establishing pressure differentials between stages. It will be observed that Figs. 2, 3, and 4 merely show a series of chilling chambers. However, it will be understood that apparatus for mixing propane and waxy oil and for preparing the mixture prior to introduction into the chilling chambers is similar to that described in Fig. 1. Likewise, the apparatus for separating the precipitated wax from the oil and propane and for separating propane from the separated oil and wax fractions and for recovering propane may be carried on similarly to that described for Fig. 1.

In Fig. 2 I have shown a simplified form for chilling the oil and propane solution by which float valves are employed for controlling the evolution of vapors from each stage. In this figure, the mixture of oil and propane containing wax is introduced into the bottom of the first chill chamber 23 via line 21 and as it rises in the column the hydrostatic head becomes less and propane is vaporized which is withdrawn from the top via line 31 controlled by valve 32 which is controlled by the level of liquid in the second chiller 23a by means of float control 38. The propane and oil from the first stage 23 flows into the second stage 23a via conduit 36, which is of sufficient size so that the flowing stream will not fill it completely and interfere with pressure equalization between the top of chiller 23 and the bottom chamber of chiller 23c for example. Likewise, the flow from the second chilling column 23a into the third chilling column 23b and from 23b to 23c is accomplished in the same manner. The propane and oil solution from chiller 23c then overflows into an accumulating chamber 24 where the cold mixture is accumulated and drawn off as required to the filters or settlers. The last chiller and the accumulator will normally be maintained at the same pressure and temperature. The chilled solution carrying precipitated wax is withdrawn from the bottom of chamber 24 via line 45 and passed to settlers or filters or other means for separating the precipitated wax from the chilled oil and remaining propane. The vaporized propane from each chill-

ing stage withdrawn via lines 31 and valves 32 pass into manifold 38 where the vapors are passed to compressors and propane recovery apparatus. The number of towers or stages of chilling is merely by way of illustration and in practice considerably more towers or stages would be desirable in order to reduce the temperature drop at each stage.

For convenience, the conduits connecting one stage with the next are made sufficiently large so that counterflow of liquid and vapor may occur without surging and thus a single vapor take-off from the top of the stage is sufficient rather than vapor take-offs from both the top and the 15 float control chamber.

Instead of employing float control valves, I may employ pressure control valves as shown in Figs. 3 and 4. In Fig. 3, pressure control valves 32 are employed on the vapors leaving each stage 20 which valves are so set as to establish a definite pressure in each stage different from that for the adjacent stage by a definite amount. These valves are of the pressure relief type which will release when the pressure on the up-stream side 25 of the valve exceeds the setting and will close when the pressure falls below the setting point. Through the controlled release of vapor from each stage, definite pressures will be established corresponding with definite temperatures varying 30 in the desired manner from stage to stage. By accurate control of the difference in pressure between stages, this difference will be maintained at a value which can properly be balanced by the hydrostatic head capable of being established by the difference in the level in the stage itself and the transfer conduit leading to the stage.

Since the proper establishment of such hydrostatic head requires the use of pressure control valves of relatively high precision of operation, 40 it may be more desirable in some cases to employ a differential pressure control valve according to the method illustrated in Fig. 4. Examples of suitable valves for this use are valves 32 operated by diaphragms 32a in which pressure can be applied to both sides of the diaphragm. The differential force generated by variation in pressure on two sides of the diaphragm is ordinarily balanced by a spring under adjustable tension so that the valve will open when the differential is too high 45 and close when the differential is too low. Thus, when the differential between stages tends to become too high so that there is danger of the liquid in the trap being blown out by the vapor, the respective valve 32 will open and will release 50 vapor until a suitable pressure differential is re-established. By proper adjustment of the valves pressure differentials between stages can be established which will permit efficient utilization of the available hydrostatic head.

60 In starting such equipment, it will usually be found desirable to fill all the stages with either the oil solution in propane or propane at the usual feed temperature and then to release propane vapor from the last stage at such a rate as 65 to give a suitable chilling rate such as not to exceed 2 or 3° F. per minute. As the vapor is evolved in the last stage, the temperature and pressure in this stage will fall and upon establishment of the desired differential pressure between this stage and the immediately preceding 70 stage, the diaphragm of the valve on the preceding stage is actuated so that vapor begins to flow from this stage and cooling of the solution in this stage starts. This operation is repeated 75 until finally the desired temperature is reached

in the last stage and the vapor outlet valves on all the stages, except possibly a few surplus stages at the beginning are in operation. Although in the drawings, these valves are shown all connected to the same header, in practice it is more desirable to have several headers operating at different pressures so as to reduce the power required for compression by avoiding unnecessary expansion and recompression.

While I have described the use of liquid propane as the internal refrigerant-diluent, it will be observed that I may employ other liquefied normally gaseous hydrocarbons for this purpose. Such hydrocarbons include methane, ethane, propane, iso-butane, butane or mixtures thereof. 10 These hydrocarbons may be obtained by rectification of casinghead gasoline by the so-called stabilizing method. They are the overhead thus obtained. They are liquefied by compression and cooling in the conventional manner and are 15 drawn off into pressure chambers where they are maintained in the liquid state until they are used.

It is to be understood that the above description is merely illustrative of preferred embodiments of my invention of which many variations 20 may be made by those skilled in the art without departing from the spirit thereof.

I claim:

1. A process for dewaxing oils which comprises mixing waxy oil with a liquefied normally gaseous 30 hydrocarbon solvent, passing said mixture continuously in a vertical confined stream, vaporizing solvent from said mixture by lessening the hydrostatic head on said mixture to chill the oil and precipitate the wax, removing the vaporized solvent at a plurality of points in said stream and separating the precipitated wax from the oil and remaining solvent.

2. A process for dewaxing oils which comprises mixing waxy oil with a liquefied normally gaseous 40 hydrocarbon solvent under pressure, passing said mixture through a plurality of chilling chambers from the bottom upwardly, maintaining the pressure at the top of said chilling chambers substantially the same as the pressure at the bottom of the next succeeding chilling chamber, vaporizing solvent in said passage through said chilling chambers by lessening of hydrostatic head, removing vaporized solvent at a plurality of stages 45 in said chilling chambers and separating precipitated wax from the oil and remaining solvent.

3. An apparatus for separating wax from oils which comprises means for mixing waxy oil with a liquefied normally gaseous solvent, a plurality 50 of vertical chillers, means for passing said oil-solvent mixture through said chillers in the direction of decreasing hydrostatic head, means in said chillers to collect solvent vaporized from said oil-solvent mixture by lessening of hydrostatic head, means for removing solvent from 55 said vapor collecting means and means to control the liquid level in said vapor collecting means.

4. An apparatus for separating wax from oils which comprises means for mixing waxy oil with 60 a liquefied normally gaseous solvent, a plurality of chilling chambers, means for introducing said mixture into the bottom of the first of said chilling chambers, means for passing said mixture from the top of each chilling chamber to the 65 bottom of succeeding chilling chambers, a plurality of compartments in said chilling chambers for trapping solvent vaporized from said oil-solvent mixture by lessening of hydrostatic head, means to control the liquid level in said com- 70 75

5 compartments, means to maintain the pressure at the top of said chilling chambers substantially equal to the pressure at the bottom of the next succeeding chilling chambers and means for removing precipitated wax from the oil and remaining solvent.

10 5. An apparatus as in claim 4 in which the means for maintaining liquid level in said compartments comprises a valve connected to said means for removing vapors from said compartments and actuated by the level of liquid in said compartments.

15 6. An apparatus for separating wax from oil which comprises a plurality of chillers, conduits connecting the top of each chiller to the bottom of succeeding chillers, means for introducing a mixture of waxy oil and liquefied normally gaseous solvent into the bottom of the first chiller, a plurality of compartments in each of said 20 chillers into which solvent vaporized by lessening of the hydrostatic head is collected, means for removing vaporized solvent from said compartments, means for controlling liquid level at a predetermined point in said compartments, said 25 means comprising a valve on said vapor removing means actuated by the level of liquid in said compartments, means for maintaining the pressure at the top of said chillers substantially the same as the pressure at the bottom of the next succeeding chiller, float control valves on the conduits connecting the top and bottom of the succeeding chillers, said float control valve being positioned at a point adjacent the bottom of said chillers and controlled by the liquid level at the 30 top of the next preceding chiller, means for removing oil, remaining solvent and precipitated wax from the top of the last chiller and means for separating the precipitated wax from the oil and remaining solvent.

40 7. An apparatus for separating wax from oil which comprises a plurality of chillers, means for passing waxy oil and solvent into the bottom of the first chiller, means for passing oil and solvent from the top of said chillers to the bottom of the next succeeding chillers, means for removing vaporized solvent by lessening of the hydrostatic head from said chillers, means for controlling the pressure at the top of said chillers substantially the same as the pressure at the bottom of the next succeeding chillers, said means comprising a valve connected to said means for removing vaporized solvent from said chillers operated by a float control positioned at the bottom of the next succeeding chiller and means for removing chilled oil, solvent and precipitated wax from the top of said last chiller.

45 8. An apparatus for separating wax from oil which comprises a plurality of vertical chillers, means for introducing a mixture of waxy oil and liquefied normally gaseous solvent into the bottom of the first chiller, means connecting the top of each chiller with the bottom of the next succeeding chiller, means for removing solvent vaporized by lessening of the hydrostatic head 50 from said chillers, means on said vapor removing means for controlling the pressure in said chillers, said means comprising a valve actuated by the vapor pressure in said chillers.

55 9. An apparatus as in claim 8 in which the means for controlling the pressure in said chillers comprises a diaphragm connected to said valves on said vaporized solvent removing means, said diaphragm being actuated by the differential pressure between adjacent chillers whereby the 60 pressure at the top of said chillers is controlled

65 to correspond substantially equal with the pressure at the bottom of the next succeeding chillers.

70 10. An apparatus for separating wax from oil which comprises means for mixing waxy oil with a liquefied normally gaseous solvent under superatmospheric pressure, means for passing said mixture under superatmospheric pressure in a vertical stream, means in said vertical stream for trapping solvent vaporized in said passage by 75 lessening of the hydrostatic head, means for removing said vaporized solvent from said vapor trapping means whereby said oil and solvent may be chilled at a gradual controlled rate and within the metastable range of supersaturation to 10 precipitate wax in large crystals and means for removing said precipitated wax from said oil and remaining solvent.

15 11. An apparatus for separating wax from oil which comprises means for commingling waxy oil with a liquefied normally gaseous solvent, a plurality of vertically disposed chillers, means connecting said mixing means with the bottom of the first of said chillers, means for passing said mixture from the top to the bottom of succeeding chillers, means within said chillers for collecting solvent vaporized from said mixture by lessening of hydrostatic head, means for maintaining a predetermined liquid level in said vapor collecting means, said means comprising a valve 20 on said vapor removing means actuated by the liquid level in said vapor collecting means, means for maintaining the pressure at the bottom of successive chillers substantially the same as the pressure at the top of the preceding chillers, said 25 means comprising a valve on said means for passing said mixture from one chiller to the next and positioned at the bottom thereof and actuated by the liquid level at the top of the next preceding chiller, means for removing chilled oil, 30 solvent and precipitated wax from the top of the last chiller and means for removing precipitated wax from the oil and solvent.

35 12. A process for chilling liquids which comprises mixing the liquid with a volatile liquid under superatmospheric pressure, maintaining a series of chilling columns with said mixture, introducing the mixture into the first of said chilling columns under a pressure substantially equal to the sum of the hydrostatic heads of liquid in said chilling columns and then passing the mixture through the columns in series relationships in the direction of decreasing hydrostatic head whereby a portion of the volatile liquid is gradually vaporized by the reduction in hydrostatic head and chilling of the mixture is accomplished, withdrawing vaporized volatile liquid from the chilling columns and withdrawing chilled liquid from the last of said chilling columns.

40 13. A process for chilling liquids which comprises mixing the liquid to be chilled with a volatile liquid refrigerant under superatmospheric pressure, maintaining a column of the mixture of liquid refrigerant and liquid to be chilled in a chilling column, introducing the mixture to be chilled into the bottom of the chilling column under a pressure substantially equal to the hydrostatic head of mixture in the chilling column plus the vapor pressure of the mixture at the top of said chilling column, chilling the mixture in said chilling column by reduction in hydrostatic head as it flows upwardly in said column, withdrawing vaporized refrigerant from the chilling column resulting from said release in pressure and withdrawing chilled mixture from the column at 45

- a point above the point of introduction of said mixture into said chilling column.
14. A process as in claim 13 in which the vaporized liquid refrigerant is withdrawn from the chilling column at a plurality of points.
15. A process as in claim 13 in which the vaporization of the volatile liquid refrigerant in said chilling column is controlled at a plurality of points in said column.
- 10 16. A process for chilling oils which comprises dissolving the oil in a volatile hydrocarbon diluent under superatmospheric pressure, maintaining a plurality of chilling columns of said mixture, said columns being connected in series, introducing the mixture into the bottom of the first chilling column under a pressure substantially equal to the sum of the hydrostatic heads of liquid in said columns and maintaining the pressure at the bottom of succeeding chilling columns substantially equal to the vapor pressure of the mixture at the top of the preceding column, passing the mixture in a direction of decreasing hydrostatic head and withdrawing volatile hydrocarbon diluent vaporized by reduction in hydrostatic head from said chilling columns.
- 20 17. A process as in claim 16 in which the vapor pressure at the top of said chilling columns is controlled by the differential pressure between adjacent chilling columns to maintain the pressure at the top of said chilling columns substantially equal with the pressure at the bottom of the next succeeding chilling columns.
- 30 18. A process for dewaxing oils which comprises mixing waxy oil with a volatile liquid refrigerant under superatmospheric pressure, maintaining a column of the mixture of liquid refrigerant and waxy oil to be chilled in a chilling column, introducing the mixture to be chilled into the bottom of the chilling column under a pressure substantially equal to the hydrostatic head of mixture in the chilling column plus the vapor pressure of the mixture at the top of said chilling column, chilling the mixture in said chilling column by reduction in hydrostatic head as it flows upwardly in said column to precipitate wax in the oil and refrigerant, withdrawing vaporized refrigerant from the chilling column resulting from said release in pressure and withdrawing chilled oil, refrigerant and precipitated wax from said chilling column at a point above the point of introduction of said mixture into said chilling column.
- 40 19. A process as in claim 18 in which the volatile liquid refrigerant is a liquefied normally gaseous hydrocarbon.
- 20 20. A process as in claim 18 in which the volatile liquid refrigerant is liquid propane.
- 5 21. A process for separating wax from oil which comprises dissolving the waxy oil in a liquefied normally gaseous hydrocarbon under superatmospheric pressure, maintaining a series of chilling columns with said mixture, passing the mixture 10 into the first of said chilling columns in series under a pressure substantially equal to the sum of the hydrostatic heads of liquid in said chilling columns, vaporizing diluent from the mixture under controlled reduction in hydrostatic head of 15 liquid in said columns to provide a uniform temperature gradient to chill the oil and diluent to a sufficiently low temperature to precipitate wax from the oil and diluent, controlling the pressure in the upper portion of said chilling columns to 20 correspond with the vapor pressure in the upper portion of the next succeeding column plus the hydrostatic head of liquid in said column, withdrawing chilled oil and diluent containing precipitated wax from the last of said chilling columns and separating the precipitated wax from the oil and diluent.
- 25 22. The method of continuously chilling a mixture of a wax-bearing oil with a normally gaseous diluent to form filterable wax crystals, which 30 comprises introducing said mixture at the base of a tower which is substantially filled with liquid, and slowly passing said mixture upwardly in said tower to gradually lower the hydrostatic pressure and permit the gradual vaporization of 35 diluent, withdrawing liberated gaseous diluent to prevent turbulence and gas-lift effects, and continuously decreasing the hydrostatic head until dewaxing temperature is reached.
- 40 23. A continuous chilling tower for use in a propane dewaxing process which comprises a tower, means for introducing a propane waxy oil mixture at the base of the tower and for withdrawing the propane waxy oil mixture from the top of the tower and a plurality of propane trap-outs 45 vertically spaced along the side of said tower, each of said trap-outs containing means for preventing the escape of liquid with vaporized propane.
